UNITED STATES PATENT OFFICE

2,070,989

MECHANISM FOR RECONDITIONING TENNIS BALLS

Harry D. Jamieson, Los Angeles, Calif.

Application October 2, 1934, Serial No. 746,622

3 Claims. (Cl. 26—29)

A principal object of my invention is to restore the original appearance and desirable playing qualities of tennis balls, the surfaces of which have become worn and soiled in use.

The useful life of a tennis ball, as prescribed by strict requirements of the game, is very brief. With expert players after use in one or two sets the ball must be discarded because of impairment of its playing qualities. Such impairment is not caused by any deterioration of the resilient qualities of the ball, but mainly, first, by a partial wearing off of the original nap of the felt covering and, second, by a slight loss in weight. The lessening of air friction and of that resulting from contact of the ball with the racket caused by the impairment of the original surface by wearing off of the nap is perhaps to the skilled player the most noticeable deficiency, the loss of weight being comparatively slight, yet both of these results of use must be corrected if the ball is to be restored to its original condition.

Specific objects of my invention are, first, to restore to its original condition the nap of the fabric covering of the ball; second, to replace weight lost in use; and, third, to clean the surface of the ball so as to present a new appearance.

It is also an important object to simplify means and mechanism for effecting such results, and to provide a process which may be easily utilized by even the most inexperienced.

Other objects and corresponding advantages will be apparent to those of skill in the art to which this invention appertains from the detailed description to follow.

In the drawing, Fig. 1 represents an end elevation of the mechanism for raising the nap of the fabric surfaces of the balls.

Fig. 2 is a section on line 2—2 of Fig. 1.

Fig. 3 is a plan view of the devices shown in Fig. 1.

Referring specifically to parts illustrated in the drawing, 4 indicates the base of a supporting frame of which 5 and 6 are vertical end walls. Power roller 7 and idler roller 8, both preferably of wood, are each surfaced with a spirally wound band of rubber fabric 9 thickly studded through its outwardly disposed surface with angularly bent needle wires 10. Rollers 7 and 8 are spaced apart as indicated in the sectional view Fig. 2 and in plan view Fig. 3, so that while the ball (designated by the numeral 11) will not fall through between the rollers it will ride freely in the channel provided by their spacing.

Shaft 12 extends axially through power roller 7, being non-rotatable with respect thereto, and

trunnions formed by the extensions of said shaft 12 beyond the ends of said rollers, are journalled, respectively, in end walls 5 and 6 as shown at 13—13. Idler roller 8 is supported by the ends of shaft 14 which extends axially through and non-rotatable with respect to said roller, said ends of shaft 14 being also journalled respectively in walls 5 and 6 as shown at 15—15.

Motor 16, diagrammatically illustrated, is geared in any conventional manner as indicated at 17 to one end of power shaft 12. A bar 18, is supported at its opposite ends on the upper surfaces of end walls 5 and 6 being held against lateral movement with respect to said walls by, and being longitudinally slidably within, bearings 15 formed by straps 19—19, secured in any suitable manner, as by screws 20 to the upper surfaces of said walls 5 and 6. Rigidly attached and extending substantially at a right angle to said bar 18 and in a spaced relation with each other are fingers 21. 22—22 designate brackets secured in any suitable manner as by screws 23 to end walls 5 and 6. In the outer ends of each of said brackets 22 are journalled sheaves 24—24. To the outer ends of bar 18 attached in any suitable manner, as by screws 25—25 are flexible straps, chains or cables 26—26 each of which passes over its corresponding sheave 24.

On each end of shaft 14 is rigidly secured a wheel 27 carrying a crank pin 28, to which crank pin is rotatably secured in any suitable manner well known in the art, the opposite ends of flexible straps or cables 26—26, said crank pins being arranged on their respective wheels 27 so that their respective throws will alternately cause longitudinal reciprocation of bar 18.

The process of reconditioning tennis balls consists, first, of treating their fabric surfaces with any of the well known wool scouring materials, preferably subjecting their surfaces to scrubbing by a brush during such cleansing operation, and second, washing them with a solution of sulphate of magnesia and water or other finely comminuted material in solution to impregnate the yarn with a weighting material. After washing, scrubbing and weighting, the balls are permitted to dry. When sufficiently dry they are placed in the spaced channel between the rollers 7 and 8, each occupying a space between an adjoining pair of fingers 21, as shown most clearly in Fig. 3 of the drawing. Power is then applied to rotate power roller 7, which rotative movement will, by contact of the balls with both rollers be communicated from power roller 7 to idler roller 8, so that the balls will be revolved in contact with 55

the needle-studded surfaces of the rollers, a different series of the needle wires thereof, slightly, by reason of the angular bend of the needle wires, pricking the nap of the ball at each of its points 5 of contact with the surfaces of the rollers such contact surfaces being continually changed as rotation proceeds. Rotary motion of idler roller 8 communicated to crank pins 28-28 will alternately through straps 26-26 passing over 10 sheaves 24-24 draw bar 18 longitudinally with respect to the rollers in alternate opposite directions, thus reciprocating fingers 21 back and forth with respect to the longitudinal axis of the rollers, which reciprocal motion will continually subject 15 new surfaces of the balls to the slight penetrating and pulling action of the needles.

What I claim and desire to cover by Letters Patent is:

1. In a device for reconditioning tennis balls, 20 the combination of a supporting frame, two cylindrical rollers, shafts extending axially through each of said rollers and forming trunnions at the respective ends thereof journalled so as to space the surfaces of said rollers from each other horizontally and in parallel alignment in said supporting frame, needle wires forming teeth slightly spaced apart and extending to a uniform distance radially from and covering the cylindrical surface of each of said rollers, said teeth being 25 uniformly slightly bent intermediate their ends so that their points extend in the same direction on each respective roller tangentially to the surface thereof, means to revolve one of said rollers 30 in the direction of the bend of said teeth, a bar 35 having its ends slidingly mounted on said supporting frame, and being disposed above in

spaced relation with and parallel to the surface of one of said rollers, a plurality of fingers spaced apart and extending laterally from said bar into the space between said rollers, and means to longitudinally oscillate said bar with respect to said 5 rollers.

2. In a device of the character described, a pair of cylindrical nappers journalled in parallel alignment and with a space less than the diameter of a tennis ball between their respective 10 surfaces, means to revolve said nappers toward each other in the direction of the inclination of their respective teeth and means to move tennis balls resting on the surfaces of said nappers in the space between them in alternate longitudinal 15 directions with respect thereto.

3. In means for reconditioning tennis balls, the combination of a supporting frame, a pair of cylindrical nappers journalled in said supporting frame in parallel alignment and with their 20 toothed surfaces spaced apart so as to form a channel of a width less at its bottom than the diameter of a tennis ball, the teeth on the upper surfaces of said nappers being inclined in a direction toward said channel, means to revolve one of said nappers in a direction toward the inclination of its teeth, means comprising one or more tennis balls to communicate said rotative movement of one napper to the other and means 25 comprising an oscillating bar having fingers extending into the space between said nappers to move said tennis balls alternately in opposite longitudinal directions with respect to said nappers. 30
